GEORGE T. WARWICK, OF SPRINGFIELD, MASSACHUSETTS, ASSIGNOR TO INTERNATIONAL MACHINE AND SCREW COMPANY, OF SPRINGFIELD, MASSACHUSETTS, A CORPORATION OF MAINE.

THREAD-FORMING MECHANISM.

1,130,226.

Specification of Letters Patent. Patented Mar. 2, 1915.

Application filed March 13, 1912. Serial No. 683,469.

To all whom it may concern:

Be it known that I, GEORGE T. WARWICK, a citizen of the United States of America, and resident of Springfield, in the county of 5 Hampden and State of Massachusetts, have invented certain new and useful Improvements in Thread-Forming Mechanisms, of which the following is a full, clear, and exact description.

10 This invention relates particularly to mechanism in an organized machine that forms screw threads on blanks by engaging the blank between a pair of rolling dies at the adjacent peripheral portion thereof; 15 which mechanism is automatically brought to engage and support the blank in proper operative position between such rolls; and in timed relation to the revolution of the rolls, to engage the blank during the portion 20 of the revolution in which the peripheral surfaces of the roll are forming the threads, and which will retreat to permit removal of the finished blank, and the insertion of a fresh blank.

25 In the accompanying drawings showing one embodiment of my invention,—Figure 1 is an elevation of a portion only of a thread rolling machine, with the arms in the open position. Fig. 2 shows the same parts with 30 the arms closed on the blank. Fig. 3 is a horizontal section taken through the center of the shaft shown in Fig. 1, and Fig. 4 is a side elevation of the parts shown in Fig. 1.

In the several views, a roll *a* is shown 35 mounted on a shaft 12, which roll is provided on its periphery with spiral grooves; and a substantially duplicate threading roll *b* is shown that is mounted on a suitable shaft, not shown, but which is parallel with 40 the shaft 12, so as to bring the threaded periphery of the roll *b* adjacent that of the roll *a*, as indicated in Figs. 1 and 2, the distance apart of these rolls being equal to the diameter of the blank that is engaged 45 between the same, such as the blank *S*; it being understood that these rolls will be rotated by suitable means at the same speed and in the same direction, whereby their adjacent peripheral portions will move in opposite directions at the same surface speed 50 and impart a rotation to the blank, as well understood in this art.

A pair of movable arms are provided for

the purpose of retaining the blank *S* at the same position between the rolls during the 55 operation, and prevent its being advanced from its engagement with the rolls; and these arms are operatively connected with the shaft 12 carrying one of the rolls where- 60 by the arms are held with their ends engag- 65 ing the blank during the portion of the revolution of the roll *a* when the thread is being formed; and after the thread has been formed the arms are caused to recede from such position to permit removal of the 70 threaded blank, and the insertion of a fresh blank.

A stationary supporting plate 25 is provided in which is a channel 5 concentric with the shaft 12 that carries the roll *a*, and 70 curved blocks 23 and 24 are mounted to slide in this channel; which blocks carry at their extremities arms 26 and 27 respectively, positioned thereon to be brought to engage the blank *S* between the rolls *a* and 75 *b* when the slides are advanced, as indicated in Fig. 2; and when these slides are retract- 80 ed, the arms will recede from the blank as indicated in Fig. 1, to permit the removal of the finished article and the insertion of a 85 fresh blank. For the purpose of moving these slides in unison to cause the arms to simultaneously engage the blank *S*, and to recede from the same, I provide a bent lever pivoted at 22 on the frame, and having one 90 arm 21 connected to the blocks 23 and 24 by links 29 and 28 respectively; the other arm 20 of the bent lever being connected with a slide 18.

On the shaft 12 is secured a cam 13 hav- 90 ing a portion of its periphery between 14 and 15 concentric for the greater portion of the periphery, while the other portion of the periphery between said two points is 95 cut away; and this periphery of the cam is 100 engaged by a roller 17 on the end of the slide 18, which slide is drawn by a spring 19 to retain the roller in constant engagement with the cam.

From this arrangement it will be under- 100 stood that when the circular portion of the cam engages the roll, the slide will be advanced to the position shown in Fig. 2, that will shift the bent lever to cause the links to advance the two slides and bring the 105 arms 26 and 27 to the closed position in en-

gagement with the blank, and the arms will be retained in this position during the greater part of the revolution, and this portion of the revolution brings the thread 5 rolling portion of the rolls to engage the blank and roll the thread thereon. When the depression in the cam is in engagement with the roll 17, the spring will advance the slide and through the lever and links will 10 retract the arms 26 and 27 from the blank, permitting its removal and a fresh blank inserted; and it will be understood that during this part of the revolution of the shaft 12 the rolls *a* and *b* will have the idle portion 15 of the periphery at the position occupied by the blank so that no operation thereon will take place. It will thus be seen that these supporting arms are automatically brought to engage a fresh blank immediately after insertion, and will continue to 20 support the blank until it is finished by the operation of the thread rolling dies; whereupon the arms are automatically moved away from the blank to permit its removal.

25 I claim:—

1. A thread-rolling machine having a pair of coacting thread forming rolls having means on the periphery to roll a thread on a blank placed between the rolls, a pair 30 of arms movable to and from the coacting adjacent portions of the rolls to support the blank in roll-engaging position, and means for reciprocating said arms from one of said rolls in timed relation.

35 2. A thread-rolling machine having a pair of coacting thread forming rolls having means on the periphery to roll a thread on a blank placed between the rolls, a pair 40 of arms movable to and from the coacting adjacent portions of the rolls to support the blank in roll-engaging position, a cam carried by one of the rolls, a slide that is spring 45 pressed against said cam so as to be reciprocated thereby, and means connecting the slide and said arms, whereby the cam will advance the arms to engage a blank between the rolls and hold the blank in such position during a portion of the rotation of the rolls, and will also cause recession of the

arms and subsequent return to holding position. 50

3. A thread-rolling machine having a pair of coacting thread forming rolls that have means on the periphery to roll a thread on a blank placed between the rolls, a pair 55 of arms movable to and from the coacting adjacent portions of the rolls, to support the blank in roll engaging position, a cam carried by one of the rolls, a slide carrying a roller and guided to reciprocate, a spring on 60 the slide for retaining the roller in engagement with the cam, a bent lever having one arm connected with said slide, and a pair of links connected to the other arm of the lever, the links being connected respectively 65 with said arms whereby the arms are moved to and from the blank as the slide is reciprocated by said cam.

4. A thread rolling machine having a pair of coacting thread forming rolls that have 70 means on the periphery to roll a thread on a blank placed between the rolls, a frame member having a channel concentric with one of the rolls, a pair of curved blocks 75 slideable in said channel, an arm carried by each block that is adapted to be brought to engage the blank in its position for engagement by the rolls, a two armed lever pivoted on the frame, a pair of links connecting said lever with said blocks respectively, a slide 80 guided for movement in the frame and connected with the other arm of said lever, a roller on the slide, a cam adjacent one of the rolls and engaged by said roller, a spring on the slide for retaining the roller in engagement with the cam, whereby the roller and slide are reciprocated to swing said lever and links to move the arms to and from the blank engaging position, and to retain the arms in such position during operation on 90 the blank by a portion of the rolls.

Signed by me at Springfield, Mass., in presence of two subscribing witnesses.
